United States Patent Office

Des. 185,229
Patented May 19, 1959

185,229

DISPOSABLE SHAKER ENVELOPE FOR CONDIMENTS OR THE LIKE

Donal J. O'Connor, Chicago, Ill., assignor to Morton
Salt Company, Chicago, Ill., a corporation of Illinois

Application September 11, 1957, Serial No. 47,707

Term of patent 14 years

(Cl. D58—2)

Figure 1 is a front perspective view of a disposable shaker envelope for condiments or the like embodying my new design;

I claim:

The ornamental design for a disposable shaker envelope for condiments or the like, as shown.
